Attorneys.

UNITED STATES PATENT OFFICE

2,166,885

AIRTIGHT RECEPTACLE

Jacob I. Wiseman, Middletown, N. Y.

Application March 28, 1938, Serial No. 198,594

1 Claim. (Cl. 24—205)

This invention relates to containers or receptacles, such as tobacco pouches, brief cases, pocketbooks, bill folds, ladies' hand bags and the compartments thereof, overnight bags and various kinds of luggage but more especially to the closing means therefor.

It is well known that the tobacco stored in a container, in the form of a pouch including a slideable closure of the Zipper type is open to the objection that it has a tendency to become dry caused by air entering the pouch through the open spaces between the prongs or teeth forming elements of the closure and further after the pouch has been opened, the user is then required to separate the walls of the pouch, which is also objectionable to form a passage of a size to permit of the bowl of the pipe to be inserted into the pouch to scoop up tobacco. It is the aim of this invention to provide, in a manner as hereinafter set forth, a receptacle having means to overcome the aforesaid objections.

It is also well known that when a Zipper closure is operated in connection with containers or receptacles, such as brief cases, ladies' hand bags, the compartments of the latter, pocketbooks, bill folds, overnight bags and various kinds of luggage, there is often a tendency of the contents of the container to creep out of the opening and engage in the prongs or teeth and in the slide of the Zipper, which is very objectionable, which results in making the operating of the slide hard and oftentimes when opening or closing the Zipper is forced, it causes the Zipper to get out of commission and in many instances to break. It is another aim of this invention to provide, in a manner as hereinafter set forth, a means to overcome the forcing of the Zipper when opening and closing it.

The invention further aims to provide, in a manner as hereinafter set forth, a container or receptacle with a closure means acting as a seal when the container is closed to prevent the contents of the latter from seeping out, when such contents are of powdered or granulative form to prevent a messy formation exteriorly of the container, when the latter is stored in a lady's hand bag or in the pocket of a garment.

One of the principal aims of the invention is to provide a pouch, or similar container having an outer closure means of the well known Zipper type and an inner closure means associated with said Zipper for preventing interference of the contents of the container with the operation of the Zipper at all times.

The invention further aims to provide, in a

manner to be referred to, a container which will be substantially air tight when closed.

The invention further aims to provide a receptacle of the character referred to in which there is an elastic and resilient element adjacent each row of Zipper teeth or prongs of the two rows comprising the usual Zipper assembly, said element extending partially above the said teeth or prongs of a row and by reason of its elasticity and resiliency closely hugging the teeth of the row adjacent one side of the latter and acting to prevent contact of the contents of the receptacle with said teeth.

It is a common expedient at the present time to provide various receptacles with a slide fastener of the Zipper type for a readily opening and closing means, but one of the greatest difficulties with this type of a receptacle is in preventing the teeth or prongs of the fastener from becoming fouled by the contents of the receptacle and thus injuring the contents as well as destroying the efficiency of the fastener. In the present invention the Zipper type fastener has secured adjacent each row of teeth or prongs an elastic and resilient element which may be entirely a flat strip of rubber or a piece of rubberized fabric. The element has a tendency to flatten out at all times and in exercising this tendency it provides a guarding wall adjacent the teeth. Thus, when a part of the contents of the receptacle projects out of the receptacle it is actually encompassed between the two walls which are provided by the resilient elements and when the Zipper is pulled shut, the two elements are forced down into closed overlapping position and away from the walls of the Zipper, which has the effect of forcing the contents of the bag back into the same. There have been provided means heretofore for providing a substantially air tight closure, but not one of these means where the two eventually overlying elements so secured at each end as to insure of their perfect operation to force the contents of the receptacle inwardly should they happen to project and at the same time provide an air tight seal.

Embodying the foregoing aims essentially and to others which may hereinafter appear, the invention consists of the novel construction, combination and arrangement of parts as will be more specifically referred to and illustrated in the accompanying drawing, wherein is shown an embodiment of the invention, but it is to be understood that changes, variations and modifications may be resorted to which fall within the scope of the invention as claimed.

The several structural features of the invention are illustrated by way of example in connection with a receptacle of the tobacco pouch type.

In the drawing:

5 Figure 1 is a perspective view looking towards the mouth of a receptacle, in accordance with this invention and with the mouth partly opened.

10 Figure 2 is a vertical sectional view of the receptacle extended and the mouth thereof opened.

15 Figure 3 is a fragmentary view in side elevation looking towards the inner face of one side of the receptacle and illustrating the form of the resilient elements.

18 Figure 4 is a fragmentary view in perspective illustrating the parts of a slide closure of the Zipper type and further showing the arrangement of the elastic elements with respect to the rows of teeth or prongs of the fastener.

20 Figure 5 is a detail illustrating the relation of the corresponding ends of the elastic elements.

25 Figure 6 is a perspective view of a closed tobacco pouch, in accordance with this invention, and

28 Figure 7 is a view similar to Figure 6 of a closed lady's hand bag in accordance with this invention.

With reference to the drawing, Figures 1 to 6 illustrate a receptacle, in accordance with this invention in the form of a tobacco pouch by way 30 of example as of rectangular contour and set up from a pair of opposed webs 8, 10 of textile fabric, leather, or other suitable material. The marginal portions of the ends and the marginal portion of one side of the webs are inturned, as at 11, 35 arranged in abutting relation and secured in such relation by the stitching 12. This structural arrangement provides a receptacle formed of a front wall 13, a rear wall 14, a pair of side walls 15, 16, a bottom 17 and an open top or mouth 18.

40 The pouch 8 has secured thereto a slidable closure of the Zipper type for opening and closing its mouth. The closure as shown includes a flexible carrier 19 for the pair of rows 20, 21 of interengageable prongs or teeth and a slide 22 for coaction with the said rows to provide for the interengagement of the teeth of the rows to close the mouth and for the separation of the teeth of the rows to open the mouth. The slidable closure is of well known form. The carrier 19 has the 45 parts 23, 23^a thereof secured to the inner faces and extending upwardly beyond the top edges of the walls 13, 14.

50 There is associated with the walls 13, 14 combined protecting, projecting, compressing and sealing elements 24, 25 respectively of like form possessing elastic and flexible characteristics and having parts shiftable to a position in overlapping relation to seal the receptacle when the slide of the fastener is operated in a direction to 55 close the receptacle and then latched in sealing position relative to the receptacle on the interengagement throughout of the teeth of said rows. The elements 24, 25 have portions thereof acted upon by the slide to overlap, when the slide is 60 moved in a direction to close the receptacle for the purpose to compress or force inwardly into the receptacle that portion of any of the contents of the receptacle which extends outwardly between the walls 13, 14 thereby preventing any 65 possibility of such portion engaging in the teeth of said rows to impair the operation of the closure. The said parts of the elements further act, when the receptacle is open to automatically extend the intermediate portions of the walls 13, 14 away 70 from each other whereby convenient access may 75

be had to the contents of the receptacle when desired, more especially if the receptacle should be in the form of a tobacco pouch. The said parts of the elements also act, when the receptacle is closed to make it substantially air tight. The 5 said parts of said elements have a tendency to flatten out and in exercising this tendency they provide a guarding wall adjacent the inner sides of the rows of teeth.

Each of the said elements consists of a flat strip 10 28 of any suitable material possessing the desired elasticity and resiliency, preferably such material will be rubber or rubberized fabric. The strip will be of a length to extend from one end to the other end of the wall with which it is associated. The strip will be narrow, of the desired thickness and be disposed on its lower lengthwise edge. Each strip, at each of its ends has the outer portion of the end edge cut out as at 27 to form each end of the strip with an inner straight edge 20 portion and a curved outer edge portion 28. The outer edge portion 28 is directed inwardly from the upper end of said inner edge portion and extends to an end of the outer lengthwise edge of the strip. Each strip consists of an inner portion 25 and an outer portion. The outer portion provides a freely movable and extendible elastic flap having its end edges provided by said curved outer portions of the end edges of the strip. The inner portion of the strip constitutes a stationary 30 resilient rectangular base 30 of rectangular contour having its end edges provided by the said straight inner portions of the end edges of the strip. The base 30 is of greater length than the flap 28. The end terminal parts of the bases 30 35 are seated against the inturned and marginal portion of the front and rear walls. The stitching 12 is employed for anchoring the ends of the bases 30 to said inturned end marginal portions. The ends of the flaps 28 are spaced from and are 40 free of direct connection to the said inturned end marginal portions.

Each strip has the inner portion thereof which constitutes the base 30 thereof secured to the inner face of a part 23 or 23^a of the carrier 19 by 45 spaced rows of stitching 31, 32. The flaps 28 of said strips extend beyond the inner sides of the rows of teeth or prongs of the closure. Each end terminal portion 33 of the flap 28 of the element 24 permanently overlaps the corresponding end 50 terminal portion of the flap 28 of the element 25.

When the slide of the closure is moved in a direction to close the receptacle, the portions of the flaps 28 between the overlapped end terminal portions of said flaps are moved to overlapping 55 relation to provide the protecting, compressing and sealing functions for the elements 24, 25. When the closure is operated to open the receptacle, the said portions of the flaps 28 between the overlapped end terminal portions of the latter 60 are automatically moved from overlapped relation to provide the projecting function of elements 24, 25, as well for protecting the rows of teeth or prongs of the closure.

With reference to Figure 7, a lady's hand bag 65 in accordance with this invention is indicated at 34.

What I claim is:

In a sealing means for a receptacle of that type 70 formed of a pair of sections having their end marginal portions and a side portion thereof inturned and secured together in abutting relation throughout to provide the receptacle with an entrance, said receptacle being formed with a closure for said entrance of the slide fastener 75

type including parts secured to the inner faces of said sections extended from the sides of said entrance and carrying on their outer faces oppositely disposed rows of interengageable teeth and 5 a slide for moving the teeth of the rows into and out of engagement, the combination of a pair of opposed combined elastic and resilient elements of strip-like form adapted to be positioned against the inner faces of said parts, each of said elements has the outer portion of its end edges cut 10 out to form each end edge of the strip with an inner straight edge portion and a curved outer edge portion directed inwardly from the upper end of said inner edge portion to an end of the outer lengthwise edge of the strip, each of said 15 strips including an inner portion and an outer portion, said outer portion providing a freely movable and extendible elastic flap having its end edges provided by the said curved outer edge

portions of the end edges of the strip, said inner portion constituting a stationary rectangular base having its end edge provided by said straight inner edge portions of the end edges of the strip, one of said flaps being extended outwardly beyond the other to overlap the latter in superimposed relation throughout when the entrance is closed to seal the receptacle, said flaps being of less length than said bases and having their end edges provide clearances for the outer portions 10 of the ends of said elements relative to the upper termini of the said turned end marginal portions, means for securing said bases to the sections of the receptacle and to said parts for maintaining the bases stationary, and means for anchoring the ends of said bases to the said turned end marginal portions. 15
